VENDING MACHINE

Bernard Leve and Hyman Leve, New York, N. Y.

Application July 5, 1928. Serial No. 290,304

4 Claims. (Cl. 312—80)

This invention relates to vending machines and more particularly to machines for vending cigarettes.

One object of the invention is to provide a compact mechanism which may be contained in a small space.

Another object of the invention is to provide a mechanism which will be proof against tampering or operation by use of improper coins.

10 A further object of the invention is to provide a simple construction which will not easily become disarranged or out of order.

A still further object of the invention is to provide a machine from which two or more kinds 15 of goods may be sold, and which may receive coins of different denominations.

A further, more specific object of the invention is to provide a plurality of dispensing elements and means for automatically changing from one 20 to another.

A still further, more specific object of the invention is to provide a mechanism which will return any coins if the machine is empty of goods.

The invention consists of the construction, combination and arrangement of parts as herein illustrated, described and claimed.

In the accompanying drawings, forming part hereof is illustrated one form of embodiment of the invention, in which drawings similar reference 30 characters designate corresponding parts, in which:

Figure 1 is a front elevation of the machine with the front cover removed showing the goods containing racks.

35 Figure 2 is a vertical section, partly broken away, taken approximately on line 2—2 of Figure 1 and looking in the direction indicated by the arrows.

Figure 3 is a plan view showing the operating mechanism in non-operated position.

Figure 4 is a vertical section broken away, taken approximately on line 4—4 of Figure 1 looking in the direction indicated by the arrows.

Figure 5 is a plan view showing the operating mechanism in operated position.

Figure 6 is a vertical section, partly broken away, also taken on line 4—4 of Figure 1.

Figure 7 is a vertical fragmentary detail taken approximately on line 7—7 of Figure 1, looking in the direction indicated by the arrows and showing the dispensing means for the package goods in normal position.

Figure 8 is a vertical fragmentary detail taken approximately on line 7—7 of Figure 1, looking in the direction indicated by the arrows, and showing

the dispensing means for the package goods in operated position.

Figure 9 is a vertical section taken approximately on line 9—9 of Figure 2 looking in the direction indicated by the arrows.

Figure 10 is a fragmentary vertical section taken approximately on line 2—2 of Figure 1.

Figure 11 is a fragmentary vertical section taken approximately on line 2—2 of Figure 1.

Figure 12 is a broken side elevation of the goods containing rack.

The drawings illustrate a machine having a goods rack on the left hand side for selling single cigarettes, i. e. one cigarette at a time, and a container on the right hand side for selling small packages containing several cigarettes. However, by making the machine larger, it may be used to vend cigars, large packages of cigarettes, confection, or in fact, any commodity which may readily be sold in packages.

Referring to the drawings, A designates a casing generally having a rear wall B, side walls C, a top D, a curved removable front wall E, a bottom F and a hinged door G. Disposed above the door G is a stationary cross member 5 secured to the side walls C. A horizontal member 6 is secured between the side wall C above the cross member 5, and supported by members 7 on the inner wall of the sides C.

Disposed on the rear side of the curved front wall E are a plurality of braces 8, preferably of metal, having their offset lower ends 9 set into recesses 10 in the top surface of the horizontal member 6. A suitable lock 11 at the top of the wall E prevents the removal of the wall E, and a pair of supporting strips 13 on the side walls C, prevent the wall E from being forced inward. Another lock 12 is disposed in and keeps the hinged door G in place.

Disposed on the inside of the rear wall B, and near the top thereof, is a supporting member 14 having an upturned lip 15 and a pair of vertical guides 16. A goods containing rack 18 is hung on the supporting member 14 by means of a overhanging lip 17 on the goods container 18, which comprises a front section 19 and a rear section 20. The sections 19 and 20 are adapted to carry a number of single cigarettes to be vended one at a time in the manner hereinafter described.

A pair of levers 21 are coupled at the point 105 22 and pivoted to the front wall of the section 19 by pivots 23 and 24 respectively. The cigarettes 25, in section 19 are forced downward by a follow-weight 26 on which is disposed a horizontally projecting lug 27. A spring 28 having one end 110

attached to the section 19 by a pin 29 and the other end attached to the levers 21 by a pin 30 holds the levers in the normal position shown in Fig. 1, so that the outer ends 34 of the levers 21 engage in slots 31 of the side walls 32 of a frame 33 which is secured to the rear wall B of the casing. A leaf spring 35 is disposed on the rear wall B at 36 and exerts pressure against the rear section 20 of the goods rack 18.

When the last cigarette 25 in the front section 19 is vended, the lug 27 on the follow-weight 26 strikes the levers 21, causing them to rock on their pivots 23 and 24. This disengages the ends 34 of the levers 21 from the slots 31. The goods rack 18, being suspended by the overhanging lip 17 and the supporting member 14, is forced forward by the spring 35 so that the bottom end of the rear section 20 occupies the same position as was occupied by the bottom end of the front section 19. The frame 33 prevents the goods rack 18 from being forced forward more than is necessary by the spring 35. Thus the sale of cigarettes is not interrupted by reason of the front section 19 becoming empty because the rear section moves forward automatically and continues to deliver the cigarettes when the machine is operated as hereinafter described.

A hook 37 is disposed on the front face of the follow-weight 26 and when the front section 19 is empty the hook 37 engages a cross bar 38 on the front face of the section 19 and prevents the weight 26 from further downward movement and consequent clogging of the operating mechanism. A pair of pins 39 on the front face of the section 19 prevent the levers 21 from being rocked more than is necessary to disengage them from the slots 31.

The container for the package goods is shown on the right hand side of Figure 1 and comprises a rear wall 40 secured to the rear wall B of the casing, a pair of side walls 41 and right angled flanges 42 on the side walls 41 which flanges do not extend to the top of the container.

Suitable perforations 40a are provided in the wall 40 so that a moistening element may be utilized between the wall 40 and the rear wall of the casing B. The packages 43 are placed in the container formed by the wall 40, the side walls 41 and the flanges 42 and are forced downward by a follow-weight 44. A pair of hooks 45 are disposed on the front face of the weight 44 so that when the container is empty the hooks 45 will engage a cross bar 46 on the flanges 42 and prevent further downward movement of the weight 44. A flange 47 is provided on the front face of the weight 44 to be used as a handle when it is desired to remove the weight to refill the container.

The entire coin operating mechanism is supported on a table 48, having a vertical supporting member 48a, which table 48 is disposed horizontally of the machine and secured to the side walls C and the rear wall B of the casing A.

Disposed on the table 48, is a supporting frame 49 on which is disposed a pair of guide members 50. A slidable plate 51 is inserted between the guide members 50, and adapted to slide above the frame 49. Disposed on the slidable plate 51 is a coin holder 52 having a guard 53. Also disposed on the plate 51 is a pull rod 54 which extends through to the outside of the machine and is provided with a head 55.

Disposed on a vertical lug 56, on the rear end of the pull rod 54, is a pin 57 surrounded by a spring 58 and adapted to work into a spring

housing 59 so that when the pull rod 54 is operated, as hereinafter described, the plate 51 will be brought back to its original position.

A portion 60 of the coin holder 52 is cut away so that when the mechanism is operated, the coin will strike a cam 61, which is pivoted at 62 to another slideable plate 68, which plate is hereinafter described. A spring 63 and a hook 63a on the plate 51 hold the cam 61 in its normal position.

One end of the cam 61 is provided with a hook 64. On the side of the cam 61 is a point 65 and a pocket 66, which is adapted to engage a lug 67 on the slideable plate 51. A second slideable plate 68 is disposed between the table 48 and the frame 49 and adapted to slide under the frame 49. Disposed on the slideable plate 68 is a vertical lug 69 adapted to be engaged by the hook 64 when the mechanism is operated.

A vertical transverse flange 70 is disposed on the lower face of the plate 68 and is provided with a pair of pins 71 surrounded by springs 72 and adapted to work into spring housings 73 in the frame 49, so that the plate 68 may be returned into its normal position after operation, as hereinafter described.

The plate 68 is provided near its rearward end with a hinged dispensing door 74, which is normally held closed by a block 75 on the table 48. A vertical transverse flange 76 on the lower face 105 of the plate 68 prevents the escape of any cigarettes 25.

An auxiliary cam 77 is pivoted at 78 to the plate 68, and is controlled by a spring 79. The cam 77 is provided with a shoulder 80 and a hook 116 81, which is adapted to engage a lug 82 on the fixed frame 49.

A hinged plate 83 having openings 84 to permit the passage of coins is disposed on the horizontal member 6 to protect the mechanism from the insertion of any implement or the introduction of any foreign substance for the purpose of tampering or defrauding the machine.

A dispensing opening 85 is provided in the table 48 immediately in front of the dispensing door 74 and communicates with a curved delivery slide 86 which is provided with a pair of guide arms 87, and delivers the goods through an opening 88, in the hinged door G of the casing A to the purchaser.

A pair of coin chutes 89 are provided on the inside face of the curved front wall E of the casing A and register with the coin holders 52. Since the mechanisms for vending the one cent goods and the five cent goods are the same, a coin support 90 is disposed on the table 48 on the one cent side, to make up the difference in size between the cent and the five cent pieces.

The operation of the mechanism is as follows:—When a proper coin is inserted in the coin chute 89 it falls into the coin holder 52 and comes to rest on the support 90, or if a five cent piece, on the table 48. As the pull rod 54 is moved forward, by the pull on the head 55, the coin holder 52 strikes the cam 77 and the hook 81 is released from the lug 82 on the frame 49. At the same time, the coin, by means of the cut out portion 60, of the coin holder 52, strikes the cam 61, swings it on its pivot 62 and causes the hook 64 to engage the lug 69 on the plate 68. As the cam 61 is moved by the pressure of the coin, the point 65 rides around the lug 67 on the plate 51 and the lug 67 is engaged by the pocket or recess 66.

This holds the hook 64 behind the lug 69 of 150

the plate 68. However, if a coin smaller than a cent is used, the cam 61 will not be moved enough to permit the point 65 to ride around the lug 67 and the pressure of the lug 67 against the outside of the point 65 will disengage the hook 64 from the lug 69. However, if the proper coin is used, the lug 67, being on the slideable plate 51, draws the cam 61 forward. Since the cam 61 is disposed on the plate 68 and the hook 64 is behind the lug 69, the plate 68 is also drawn forward.

As the dispensing door 74 passes the block 75, it opens by gravity and the cigarette 25 is dropped through the opening 85 in the table 48 and brought to the purchaser by means of the curved slide 86, the guides 87 and the opening 88.

The cam 77 in conjunction with the hook 81 and the lug 82 on the frame 49, operates as a lock to prevent the plate 68 being moved except by movement of plate 51, thus providing a further safeguard against fraud.

As the plate 68 is drawn forward, the rear part thereof takes the position normally occupied by the door 74 and prevents more than one cigarette being delivered. As the plate 68 is brought back to its normal position by the spring 72, the door 74 moves backward and is closed when it strikes the block 75 on the table 48, and the next succeeding cigarette is dropped into place to be vended.

When the coin in the coin holder 52 passes the end of the cam 61, the pressure is removed and the coin drops through an opening 91 in the table 48 into a coin box 92, which is disposed on a retaining shelf 93 secured to the side walls of the casing A.

Since it is necessary to return the coins when the machine is empty, a coin return means is provided, and illustrated in Figures 10 and 11, as follows:

When the front section 19 of the goods rack 18 is empty the rear section 20 is brought forward as previously described. As the last cigarette in the rear section 20 is sold, a projecting lug 95 on a follow-weight 94 in the rear section 20 strikes the rear arm 96 of a lever 97 which is pivoted at 98 to the vertical supporting member 48a of the table 48.

The forward arm 99 of the lever 97 is connected at 100 to the horizontal arm 101 of the bell-crank lever, which is pivoted at 102 to the vertical supporting member 48a of the table 48. The vertical arm 103 of the bell-crank lever has a transverse rod 104 disposed at its lower end.

A coin deflector 105 is hinged at 106 to the lower face of the table 48 and normally hangs out of the path of movement of a coin in dropping through the opening 91 into the coin box 92. However, when the lug 95, which projects past the rear section 20, on the weight 94, strikes the arm 96 of the lever 97 it causes the transverse rod 104 to swing the coin deflector 105 into the path of movement of a coin falling through the opening 91.

An opening 107 is provided in the rear wall of the coin box 92 and the deflected coin falls through the opening 107 instead of into the coin box and is returned to the operator by means of the curved delivery slide 86 and the opening 88 in the door G.

The coin operating mechanism for the packages of cigarettes is the same, but due to the difference in size, the dispensing means is different, as follows:

The plate 68 is provided with a hinged dis-

pening door 108, which is normally held closed by the rear portion of the table 48. Immediately behind the door 108 is a vertical flange 109 on the plate 68, which flange 109 normally holds a leaf spring 110, which is connected at 111 to the rear wall 40 of the package container, out of the path of movement of the packages.

As the flange 109 moves forward with the plate 68, the spring 110 is released and a toothed flange 112 on the spring 110 grips the next succeeding package 43 and prevents further travel, while the door 108 falls open and drops the package 43, which is being vended, through the opening 113, of the table 48, onto the curved delivery slide 86 and to the purchaser through the opening 88 in the door G.

As the plate 68 returns, after the sale, the door 108 is closed by the rear portion of the table 48, the flange 109 presses the spring 110 backward and the toothed flange 112 releases the next package and permits it to fall into a position to be vended.

The offset lug 114 is disposed on the face of the weight 44 and adapted to pass around the flanges 42 of the package container. The lug 100 114 projects past the side walls 41 of the package container and when all of the packages are sold, operates a coin return mechanism similar to and in the same manner as the one previously described.

In filling the goods rack 18 with single cigarettes, the front and rear sections 19 and 20 may be filled either from the top or the bottom. In order to prevent the cigarettes from falling out of the sections 19 and 20, when the rack is being replaced, and in order to provide a handle by means of which the rack 18 may be easily replaced, a key 115 is used.

The key 115 has a bent portion 116, which may be used as a handle, a curved top end 117, and a flange 118 at its bottom end. When the sections 19 and 20 have been filled with cigarettes, the curved top end 117 of the key 115 is inserted in an opening 120 of a horizontal flange 119 on the front of section 19.

A second horizontal flange 121 is provided near the bottom of section 19 and has a recess 122, (shown in Figure 1.) The shaft of the key 115 is set into the recess 122 and held in place by a latch 123, on the flange 121. The flange 118 of the key 115 projects across the bottom of the section 19 and 20 and prevents the cigarettes from falling therefrom. The key 115 is used as a handle to replace the goods rack 18 in the casing A. When the goods rack 18 is in place, the key 115 is turned to one side, so that the flange 118 clears the front section 19. The latch 123 is opened and the key is removed.

Another latch 124 is pivoted at 125 to the top of the rear section 20 and adapted to engage a projecting lug 126 on the front section 19 so that the two sections will maintain their positions with respect to one another.

In filling the container for package goods, the weight 44 is removed from the container by means of the flange or handle 47 and since the flanges 42 do not go all the way to the top of the container, the packages are inserted in the container at a point above the end of the flanges 42 and the weight 44 is replaced in the same manner.

A mirror 127 is disposed in the front wall E of the casing A.

Having thus fully described the invention what

is claimed as new and desired to be secured by Letters Patent, is:

- 5 1. A vending machine comprising a casing, a plurality of goods containers suspended in the casing and means for shifting the containers comprising a spring, a pair of pivoted arms normally engaging slots in a fixed frame, and a weight to release said arms from said slots.
- 10 2. A vending machine comprising a casing, a plurality of goods containers disposed in the casing, a gravity operated door beneath the goods containers and means to successively align the goods containers with the door comprising a spring, a weight disposed in one container and a pair of pivoted arms disposed on the same container, said arms being normally engaged in slots in a fixed frame and said weight being adapted to release said arms from said slots.
